DESIGN FOR A SANDAL

Jerome H. Louchheim, Jr., Philadelphia, Pa.

Application March 14, 1938, Serial No. 75,790

Term of patent 3½ years

To all whom it may concern:

Be it known that I, Jerome H. Louchheim, Jr., a citizen of the United States, residing at Philadelphia, in the county of Philadelphia and State of Pennsylvania, have invented a new, original, and ornamental Design for a Sandal, of which the following is a specification, reference being had to the accompanying drawing, forming part thereof.

I claim:

The ornamental design for a sandal, as shown.
